UNITED STATES PATENT OFFICE.

ALEXANDER H. WOOD, OF PETROS, TENNESSEE.

BUFFER FOR RAILWAYS.

1,156,649.

Specification of Letters Patent.

Patented Oct. 12, 1915.

Application filed December 16, 1914. Serial No. 877,471.

To all whom it may concern:

Be it known that I, ALEXANDER HAMILTON WOOD, a citizen of the United States, residing at Petros, in the county of Morgan and State of Tennessee, have invented a new and useful Improvement in Buffers for Railways, of which the following is a specification, reference being had to the accompanying drawing.

10 My improvement relates particularly to buffers placed upon railroad tracks in such manner as to yieldingly engage cars running upon said tracks and gradually bring the cars to a stop.

15 One of the objects of the invention is to provide such a buffer which will permit a large measure of rearward yielding after impact by the car and which will return forward to its normal position after the car has 20 been stopped, and by such movement move the car in the return direction, and preferably, bring it to rest in the position it occupied at the moment of impact with the buffer. The entire buffer is mounted on 25 wheels resting and adapted to travel on the track. And provision is preferably made to allow the buffer to travel to both sides of its normal position, as hereinafter described. Thus my improved structure may be termed 30 a buffer car, and it will be seen that this car is normally stationary.

In the accompanying drawings, Figure 1 is a side elevation of a structure embodying my improvement; Fig. 2 is an end view 35 looking toward the right of the structure as shown in Fig. 1; Fig. 3 is a section on the line, 3—3, of Fig. 1.

Referring to said drawings, R, R, are 40 fixed track rails supported on ties, T.

45 C is one end of a rotary tipple structure which is arranged for rotation on an approximately horizontal axis located above and approximately parallel to the rails, R. In the form shown in the drawings, said 50 structure rises slightly from left to right. Said tipple is in the form of a tubular frame, supported on stationary rollers, B. This form of tipple is well known and need not be described in detail. The tipple has two 55 track rails, D, the ends of which register with the rails, R, and rise a little from left to right; and it is to be assumed that at the right of the rotary tipple, there is a fixed track inclining toward the tipple and registering with the track in the tipple in the

usual manner, so that cars may run by gravity from any point on said inclined stationary track into the tipple, as has heretofore been done.

The function of the buffer in the mechanism illustrated by the drawings is to stop the car when it runs by gravity into the tipple. The normal position of the buffer is such as to cause impact with the car when the latter attains its proper position in the tipple. But when such impact occurs, the buffer yields and allows the car to move leftward out of the tipple until the momentum of the car has been entirely overcome, and then the buffer travels rightward, pushing 70 the car in the same direction, until the normal position of the buffer has been resumed. In the particular form of the apparatus illustrated by the drawings, provision is made to allow the buffer to pass rightward 75 of its normal position, on account of momentum acquired by the buffer and the car while moving toward the position of rest.

The buffer car, E, is supported by four wheels, 1, 1, resting on the rails, R, R. On 80 the buffer car, E, are a bearing, 2, and a bearing, 3, and an abutment, 4, arranged on a horizontal line which is approximately in alinement with the axis of the rotary tipple, the bearings, 2 and 3, being on the right 85 hand or forward portion of the buffer car. In the bearings, 2 and 3, is a reciprocating and rotary shaft, 5. On the right hand end of 90 said shaft is a rotary, disk-form buffer head, 6, presenting a flat face toward the tipple. Said head has a hub, 7, which is closed at the right and receives the right hand end of the shaft, 5. Between said hub and the bearing, 2, a sleeve or hub, 8, loosely surrounds the shaft, 5. Braces, 9, extend from 95 said sleeve outward and rightward to the head, 6, and are joined to the latter, said head, braces, and sleeve forming a rigid structure rotatable on the shaft, 5. An expanding coiled spring, 10, surrounds the shaft, 100 5, between the bearing, 2, and the sleeve, 8, and bears endwise against said bearing and sleeve. A collar, 11, surrounds the shaft, 5, at the right of the sleeve, 8, and prevents rightward movement of said sleeve on the 105 shaft. Leftward movement of the sleeve, 8, braces, 9, and head, 6, is prevented by engagement of the adjacent end of the shaft in the hub, 7.

When pressure is applied against the right 110

hand side of the head, 6, in a direction approximately parallel to the length of the shaft, 5, said head and said shaft are pressed leftward, the shaft sliding in the bearings, 2 and 3, and the spring, 10, being compressed between the bearing, 2, and the sleeve, 8, such movement continuing, if the pressure is sufficient, until the left hand end of the shaft rests against the abutment, 4.

15 Between the track rails, R, R, are two grooved pulleys, 13 and 14, mounted in the same upright plane on axles which are horizontal and transverse to the length of the track, and far enough apart to allow a rope, 15, cable, or chain, or similar tension member, 15, to extend downward between said pulleys. The upper end of said tension member is secured to an eye, 16, on the forward portion of the buffer. The lower portion 20 of said tension member is secured to a weight, W. The structure below the pulleys, 13 and 14, is open downward far enough to permit the weight, W, to stand at such depth as will allow a tension member, 15, 25 of sufficient length to permit the buffer to move to the left as far as may be desired for conveniently and safely receiving impact from a car in the tipple and bringing such car to a stop. When the buffer is pressed 30 toward the left, it draws the tension member upward over the grooved pulley, 13. The weight, W, is such as to permit its lifting by the stress put upon the buffer when the buffer is struck by a car moving into the 35 tipple and to move the buffer and the other car toward the right as soon as its momentum has been overcome.

When, after the car running into the tipple has been stopped, the buffer car is moved 40 toward the right by the action of the weight, W, the tension member, 15, runs over the pulley, 13, until the eye, 16, crosses an upright line extending between the grooved pulleys, 13 and 14. Then the tension member, 15, bears against the grooved pulley, 14, 45 and travels upward and rightward over said pulley, the weight, W, being lifted and yieldingly resisting the movement rightward of the normal position of the buffer car—the position it occupies when the eye, 50 16, is in said upright line. That position brings the head, 6, into position to bear against the car when the latter stands in its proper place in the tipple. As above indicated, the weight, W, is sufficient to make 55 the buffer assume and retain its normal position against the pressure of a car which is stationary, or nearly so, in the tipple.

When the tipple is rotated, the car standing 60 therein bears against the head, 6, and the latter rotates by such engagement with said car. During such rotation, said head may turn on the shaft, 5, or said head and said shaft may turn in unison, the shaft turning in the bearings, 2 and 3, this de-

pending upon whether the greater resistance to rotation resides in the hub, 7, of the sleeve, 8, or in the bearings, 2 and 3.

The area of the right hand or forward face of the head, 6, is to be sufficient to 70 properly engage the end of a car running into the tipple. Usually such cars have bumpers. In some cases these are set close to the middle line of the car body and in other cases they are at or near the corners 75 of the car body. If cars varying in this respect are run into the same tipple for discharging, the face of the head, 6, should be large enough to engage the bumpers which are set the farthest from the middle line of 80 the car.

The resistance of the coiled spring, 10, and the distance through which it may be compressed are intended to adapt the head, 6, to yield leftward for the gradual over- 85 coming of the inertia of the buffer car and the weight, W, so that the shock from impact against the buffer may be reduced to the minimum.

The tipple is preferably made long enough 90 to receive and turn a group or "trip" of cars at one time. The momentum of such a trip of cars, is, of course, greater than the momentum of a single car, and hence there is greater need for efficient means for controlling and overcoming such momentum and then "spotting" the trip of cars in proper position within the tipple preparatory to turning. In this connection, the provision 95 for movement of the buffer car in both directions from its normal position and then definitely bringing it to rest in its normal position is very important.

It will be observed that the buffer is freely movable on the track in either direction 100 from the normal position of the buffer, and that the distance through which the buffer may move from its normal position is limited only by the length of the tension member which supports the counter-weight. 105 This makes possible a range of movement which can not be attained with a buffer of which some part is stationary. The range of movement from the normal position may be five or ten or twenty-five or one hundred 110 feet, or more. This adapts the buffer to receive and control and bring to rest in a precise position a trip comprising a considerable number of heavy cars running at a relatively high speed. The mechanism is 115 more than a railway buffer in the ordinary sense. While it does all that is done by an ordinary buffer, its wide range of movement both ways from the position of rest adapts it to serve the additional purpose of 120 "spotting" cars used for any purpose.

I claim as my invention,

1. In an apparatus of the nature described, the combination of a rotatable and longitudinally yielding buffer head located 130

at approximately the height of a car body, and means for supporting and rotating a car in engagement with said buffer head, the car and the buffer head rotating in unison, substantially as described.

2. In an apparatus of the nature described, the combination of a rotary track section, a body, a buffer head on said body, wheels supporting said body for travel of the body on the track, and means acting yieldingly at a point on the track to move said body on said wheels to a chosen position on the track for bringing a running car to rest on said track section, substantially as described.

3. In an apparatus of the nature described, the combination of a rotary track section, a body, a rotary buffer head on said body, wheels supporting said body for travel of the body on the track, and means acting yieldingly at a point on the track to move said body on said wheels to a chosen position on the track for bringing a running car to rest on said track section, substantially as described.

4. In an apparatus of the nature described, the combination of a rotary track section, a body, a rotatable and endwise movable buffer head on said body, wheels supporting said body for travel of the body on the track, and means acting yieldingly at a point on the track to move said body on said wheels to a chosen position on the track for bringing a running car to rest on said track section, substantially as described.

5. In an apparatus of the nature described, the combination of a buffer body, wheels supporting said body for travel of the body on the track, and means engaging the buffer body and acting yieldingly relative to a chosen point on the track to permit said body to move to either side of said point for bringing a running car to rest on said track at a fixed distance from said point, substantially as described.

6. The combination of an endwise movable railway buffer comprising a shaft parallel to the track, a rotatable head on said shaft, and constantly acting means tending to move said head parallel to the track, and yielding means acting to place said buffer at a chosen position on the track, substantially as described.

7. The combination of a railway buffer movable lengthwise on a track and comprising bearings parallel to said track, a shaft in said bearings, a head on said shaft, and a spring tending to move said shaft in the direction of said head, and yielding means acting to place the buffer at a chosen position on said track, substantially as described.

8. A railway buffer movable lengthwise on a track, said buffer comprising bearings parallel to the track, a shaft in said bearings, a head and sleeve and braces on said

shaft, and yielding means tending to move said shaft in the direction of said head, substantially as described.

9. The combination of a railway buffer comprising supporting wheels and a shaft parallel to the track, a rotatable head on said shaft, and constantly acting means tending to move said head from the body of said buffer, and yielding means acting to place said buffer at a chosen position on the track, substantially as described.

10. The combination of a railway buffer comprising supporting wheels, bearings parallel to the track, a shaft in said bearings, a head on said shaft, and a spring tending to move said shaft in the direction of said head, and yielding means acting to place the buffer at a chosen position on the track, substantially as described.

11. The combination of a railway buffer comprising supporting wheels, bearings parallel to the track, a shaft in said bearings, a head and sleeve and braces on said shaft, and yielding means tending to move said shaft in the direction of said head, substantially as described.

12. In an apparatus of the nature described, the combination of a body, wheels supporting said body for travel of the body on the track, a buffer head supported by said body, a counter-weight, a tension member connecting said counter-weight to said body, and relatively fixed guiding means adapted to act in either direction parallel to the track to permit said body to move, under the restraint of said counter-weight, to either side of said guiding means, to adapt the apparatus to bring a running car to rest at a fixed distance from said guiding means, substantially as described.

13. The combination of a buffer car comprising wheels for supporting the car on a track, a movable track section, yielding means acting relative to a point on the track and connected with the car for drawing the latter to said point for bringing another car to rest on said track section, substantially as described.

14. In an apparatus of the nature described, the combination of a fixed track and a movable track section, a buffer body, wheels supporting said body on said stationary track, a buffer head on said body, and means on said track near said movable track section acting yieldingly to move said body on said wheels to a chosen position on the track for bringing a running car to rest on said track section, substantially as described.

15. In an apparatus of the nature described, the combination of a stationary track and a movable track section, a buffer body, a rotary buffer head on said body, wheels supporting said body for travel on said track, and means on said track near said movable track section acting yieldingly to

- move said body and said wheels to a chosen position on the track for bringing a running car to rest on said track section, substantially as described.
- 5 16. In an apparatus of the nature described, the combination of a stationary track, a movable track section, a buffer body, a rotatable and endwise movable buffer head on said body, wheels supporting said body for travel of the body on the track, and means located on said track near said movable track section acting yieldingly to move said body on said wheels to a chosen position on the track, substantially as described.
- 10 17. In an apparatus of the nature described, the combination of a stationary track, a movable track section, a buffer body, a buffer head on said body, wheels supporting said body on said track, and means located on said stationary track near said movable track section acting yieldingly at either side of a chosen position on the track to move said body on said wheels into said position, substantially as described.
- 15 18. In an apparatus of the nature described, the combination of a stationary track, a movable track section, a buffer body, wheels supporting said body for travel of the body on said track, a buffer supported by said body, a counter-weight, a tension member connecting said counter-weight to said body, and a relatively fixed guide member located on said stationary track near said movable track section for guiding the tension member whereby the apparatus is adapted to bring a running car to rest on said track section, substantially as described.
- 20 19. In an apparatus of the nature described, the combination of a stationary track, a movable track section, a buffer body, wheels supporting said body for travel of the body on the stationary track, a buffer

head supported by said body, a counter-weight, a tension member connecting said counter-weight to said body, and a relatively fixed guide pulley located on said stationary track near said movable track section for guiding the tension member whereby the apparatus is adapted to bring a running car to rest on said track section, substantially as described.

25 20. In an apparatus of the nature described, the combination of a stationary track, a movable track section, a buffer body, wheels supporting said body for travel of the body on the stationary track, a buffer head supported by said body, a counter-weight, a tension member connecting said counter-weight to said body, and relatively fixed guiding means located on said track near said movable track section and adapted to act in either direction parallel to the track, substantially as described.

30 21. In an apparatus of the nature described, the combination of a stationary track, a movable track section, a buffer body, wheels supporting said body for travel of the body on the stationary track, a buffer supported by said body, a counter-weight, a tension member connecting said counter-weight to said body and to guide pulleys located in relatively stationary bearings on said stationary track near said movable track section and adapted to guide said tension member in either direction parallel to the track, substantially as described.

In testimony whereof I have signed my name, in presence of two witnesses, this fourth day of December, in the year one thousand nine hundred and fourteen.

ALEXANDER H. WOOD.
